Specification for Design.

Patented Aug. 7, 1917.

Application filed June 20, 1917. Serial No. 175,806. Term of patent 3½ years.

To all whom it may concern:

Be it known that we, EUGENE IRVING HANSON, a citizen of the United States of America, and a resident of New Rochelle, county of Westchester, and State of New York, and ROBERT SCHEY, a citizen of the United States of America, and a resident of the borough of Manhattan, city and State of New York, have invented a new, original, and ornamental Design for a Textile Fabric, of which the following is a specification, reference being had to the accompanying drawing, showing our design.

The drawing shows a face view of a portion of fabric bearing our design.

Copies of this patent may be obtained for five cents each, by addressing the "Commissioner of Patents, Washington, D. C."

The design is intended to be repeated lengthwise and transversely of the fabric, substantially as indicated in the drawing.

The essence of our invention resides in the general appearance of the design, substantially as shown and described; it being understood that our claim includes all substantial equivalents of the design as shown and described.

We claim:

The design for a textile fabric substantially as shown and described.

EUGENE IRVING HANSON.
ROBERT SCHEY.
